DUSTING DEVICE

Filed Nov. 1, 1939

UNITED STATES PATENT OFFICE

2,265,493

DUSTING DEVICE

Ralph R. Root, Lakewood, Ohio, assignor to The Root Manufacturing Company, Cleveland, Ohio, a corporation of Ohio

Application November 1, 1939, Serial No. 302,392

11 Claims. (Cl. 43—147)

This invention relates to dusting devices for distributing dusts of the insecticide and fungicide type and as its principal object aims to provide an improved device of this kind in which a more efficient and satisfactory feeding and distribution of the dust is obtained.

In all prior dusting devices which have come to my attention, the feeding of the dust to the air stream has been more or less irregular and has resulted in an erratic operation in which the dust cloud delivered is at times too light or thin and at other times too dense or heavy, and therefore, as another object of my invention, I aim to overcome this difficulty by providing an improved dusting device in which suction, or suction combined with an auxiliary air stream or blast, is used for feeding the dust to the main air stream whereby I obtain a substantially complete atomization and accurately regulated feeding of the dust with the result that for a given setting of the device the dust clouds produced thereby will be of substantially uniform density or dust content.

A further object of my invention is to provide an improved dusting device of the type having means for creating an air blast and in which means is provided for utilizing a portion of the air blast for feeding the dust to the main air stream.

Still another object of my invention is to provide an improved dusting device, of the type above referred to, in which adjustable valve means is arranged to control the feeding of the dust to the air stream.

It is also an object of my invention to provide an improved dusting device having a dust supply chamber from which dust is fed to the air stream and also having a magazine adapted to contain an additional or reserve supply of dust, and in which the construction and arrangement of the supply chamber and magazine produces new results and advantages such as the transfer of dust to the supply chamber from the magazine by merely swinging the device to cause agitation or shifting of the body of dust contained in the magazine.

My invention may be further briefly summarized as consisting in certain novel combinations and arrangements of parts hereinafter described and particularly set out in the appended claims.

In the accompanying sheet of drawings,

Fig. 1 is a front elevation showing a dusting device constructed according to my invention;

Fig. 2 is a partial longitudinal sectional view of

the device taken substantially as indicated by line 2—2 of Fig. 1;

Fig. 3 is a transverse sectional view taken through the device as indicated by line 3—3 of Fig. 1;

Fig. 4 is a partial sectional view taken through the delivery end of the device and illustrating the construction thereof on a larger scale;

Fig. 5 is another transverse sectional view taken through the device as indicated by line 5—5 of Fig. 2; and

Fig. 6 is a partial elevational view of my dusting device showing the same applied to another use.

More detailed reference will now be made to the accompanying drawing in which I show a dusting device embodying my improvements and although the dusting device shown in this instance is of the type in which the air pump must be continuously operated, it will be understood, of course, that the invention can also be embodied in various other forms of construction and types of dusting devices.

The embodiment of my dusting device shown in the drawing, comprises in general, a pump 10 for creating a blast or stream of air, a container section 11 adapted to contain a supply of dust and having means for feeding the dust to the air stream, and a magazine 12 in which a reserve supply of dust may be carried.

As shown in Fig. 2, the pump 10 may comprise a tubular cylinder 13 having therein a slideable piston 14 adapted to be reciprocated by a handle 15a and an actuating rod 15 connected with the handle and extending into the cylinder through the cover 16. The piston 14 may be of the type having a cup-shaped washer 17 formed of rubber, leather or other suitable flexible material. The cover 16 may be of sheet metal construction and appropriately shaped for connection with the outer end of the cylinder 13. This cover may have a bearing sleeve or bushing 18 thereon formed of wood or any other suitable material and through which the actuating rod 15 extends. The inner end of the cylinder may have a dished end wall 19 mounted therein and the blast or stream of air created by the inward movement of the piston 14 may be delivered from the cylinder through the axially extending delivery tube 20.

The container section 11 forms a chamber 21 adapted to contain a quantity of dust which is to be fed to the air blast or stream being delivered from the cylinder 13 to thereby create a dust cloud. This container section may be of cylindrical or tubular form and may be arranged as

an axial extension of the cylinder 13 of the pump 10 with its upper end engaging in the recess of the dished wall 19. The lower end of the container section 11 may be closed by a cover-like or plug-like unit or assembly 23 in which means is provided for feeding the dust from the chamber 21 to the air blast or stream, as will be presently explained. The air delivery tube 20 may have its upper end mounted in an opening of the dished wall 19 and may extend axially of the container section 11 to, or into, the assembly unit 23.

This unit 23, which closes the lower end of the container section 11 and embodies the dust feeding means, can be best described by reference to Fig. 4 in which it will be seen that the unit includes inner and outer dished sections or covers 25 and 26. The dished inner cover 25 may be of a size such that its annular skirt or flange 25a fits snugly in the lower end of the container section 11. The dished outer cover 26 may be of a size such that its annular flange or skirt 26a snugly telescopes over the lower end of the container section 11.

The unit 23 also embodies a suction chamber or feed chamber 28 adapted to contain an immediate or temporary supply of dust and having a relatively small volume as compared with the volume of the supply chamber 22. The feed chamber 28 may be formed by a dished member 29 which may be similar to the inner cover 25 and may fit snugly in the container section 11 with its annular flange or skirt 29a extending toward and engaging the inner cover 25. For admitting dust to the feed chamber 28 from the supply chamber 21, I provide the transverse wall of the member 29 with an opening 30, of appropriate size, across which a screen 31 may extend.

A sleeve or tube section 32 mounted in an opening of the transverse wall of the inner cover 25 surrounds or telescopes the outer end of the delivery tube 20 and forms an axial extension thereof. The dished member 29 has an opening accommodating the sleeve 32 and may be connected with the sleeve as by the solder 32a. The sleeve 32 has one or more radial openings 33 therein for feeding dust from the feed chamber 28 into the blast or stream of air being discharged through the delivery tube 20 and the extension tube or sleeve 32.

To obtain the above-mentioned efficient atomization and uniform feeding of dust from the chamber 28 into the air blast or stream being delivered, I create a suction in the opening or openings 33 tending to draw the dust into the air blast through these openings. For creating this suction in the openings 33, I provide a restriction in the air delivery passage in advance of these openings. This restriction may be in the form of a flange or disk 34 extending transversely of the air delivery passage and having an opening or orifice 35 of appropriate shape and area therein. In this instance the restriction 34 is an in-turned flange formed on the inner end of a rotary valve 36 which will be presently referred to. When the blast or stream of air being delivered by the pump 10 through the tube 20 passes through the restricted opening or orifice 35, its pressure and velocity characteristics are so changed as to create a suction in the openings 33 acting in a direction to feed dust from the chamber 28 into the air blast.

To permit or facilitate this suction feeding of dust through the openings 33, I may provide an air stream or auxiliary air blast which acts to

transfer dust from the supply chamber 22 to the feed chamber 28 and also to assist the feeding of dust from the chamber 28 through the openings 33 into the main air blast or stream. This auxiliary air stream or blast may be obtained simply as the result of the suction created in the openings 33 and the entry of air into the device through an appropriate vent passage or by leakage into the magazine 12. However, I prefer to provide a more definite and stronger flow or blast of air for this purpose through the screen 31 into the feed chamber 28. In obtaining this auxiliary air stream or blast, I may utilize a portion of the main blast or stream of air being delivered through the tube 20. To this end I may provide the tube 20 with a depending branch tube 38 on the lower side thereof which is arranged to divert a portion of the air blast and direct the same against or through the screen 31. The open outer end of the branch tube 38 is arranged opposite the screen 31 and is spaced a short distance therefrom so that the auxiliary air blast delivered through this branch tube will force or carry dust from the supply chamber 22 through the screen into the feed chamber 28. In thus passing through the screen the dust will not only be screened for the removal of lumps and foreign articles which might otherwise clog the openings 33, but is also sifted so that the quantity of dust contained in the feed chamber 28 will be in a loose and aerated condition for complete atomization and free passage through the openings 33 into the main air blast.

For controlling the feeding of dust into the air blast through the openings 33, I provide the above-mentioned valve 36, which, in this instance, is a rotary valve of tubular or sleeve-like form and is mounted in the tube section or sleeve 32. The valve 36 may be provided with radial openings 40 similar in number and size to the openings 33 so that by rotation of the valve in the sleeve 32, the openings 33 can be opened full or can be opened partially to any desired extent or area for feeding a controlled amount of dust into the main air blast.

The rotary valve 36 may be actuated by providing thereon a lever 41, which is preferably in the form of a spider, as shown in Figs. 4 and 5, and has radial arms 42 extending through circumferentially spaced arcuate guide slots 43 formed in the outer cover 26. One of these arms may be longer than the others and may extend beyond the cover as a handle or actuating portion 42a by which the valve 36 may be conveniently actuated or adjusted by the person operating the dusting device. The spider 41 is retained against axial movement by engagement of its arms 42 in the guide slots 43 and the valve 36 is thereby located or positioned in the sleeve 32 so that the valve openings 40 will register with the openings 33 when the valve is rotated. The valve can also be located axially by constructing the spider so that the arms thereof are yieldable whereby the flange 34 of the valve will be resiliently pressed against the shoulder 45 formed by the outer end of the delivery tube 20.

With the construction and arrangement above described for the feeding and atomizing unit 23, it will be seen that this unit can be constructed as a separate assembly and thereafter readily fitted or applied to the lower end of the dusting device.

The magazine 12, which, as mentioned above, is adapted to contain a reserve supply of dust, may be of any appropriate size and shape, but as shown in the drawing, is preferably in the form

of a cylindrical housing 47 having end walls 48 and 49. The magazine is preferably mounted on the container section 11 adjacent the upper end thereof with the cylindrical wall 47 coaxial with the container section and with the latter extending through a central opening of the lower end wall 48. The upper end wall 49 of the magazine may also have a central opening in which the dished member 19 is mounted and the magazine may be connected with the pump cylinder 13 and the container section 11 by solder or like material indicated at 50.

The magazine is in communication with the interior of the container section 11, that is, with the supply chamber 21 through an opening 51 provided in the container section 11 adjacent the upper end thereof and when the operator wishes to transfer dust from the magazine to the supply chamber 21, he agitates or shifts the body of dust contained in the magazine so that some of this dust will spill through the opening 51. This can be easily brought about during the use of the dusting device by simply swinging the device so as to cause its delivery end to travel in an arc up and over the shoulder of the operator. One such sweep of the device will readily cause a part of the reserve supply of dust to be transferred from the magazine to the supply chamber 21.

For charging or filling the magazine 12 I provide a filling opening 52 in the curved wall 47 thereof and this may be closed by a cover 53 which is correspondingly curved to fit snugly against the outer surface of the magazine wall. This cover may be mounted on a hinge 54 and may be held in closed position by means of a latch, preferably in the form of a spring bar 55. This spring bar may have an intermediate portion thereof anchored on the cover 53 as by means of the clip 56 and its oppositely projecting end portions may engage in slotted ears or lugs 57 mounted on the end walls of the magazine. When the cover is swung to its closed position and the resilient end portions of the locking bar 55 are sprung so as to engage in the slotted ears 57, as indicated in Fig. 1, the cover will be drawn tightly against the wall of the magazine and will prevent the leakage of dust therefrom.

During the use of my improved duster, the operator carries the device by grasping the cylinder 13 with one hand and operates the pump 10 by grasping the handle 15a of the actuating rod with the other hand. As above explained, the operation of the pump causes successive blasts of dust-laden air to be delivered through the rotary valve 36 and the opening 26a of the outer cover. The device is ordinarily operated with the delivery end lowered, that is pointing toward the ground, in which condition the supply of dust contained in the supply chamber 21 gravitates to a position in front of the screen 31. However, since the feed chamber 28 is capable of holding a quantity of dust adjacent the openings 33, and since the feeding of dust through the openings 33 is brought about by suction, or suction in combination with an auxiliary air blast or stream, it will be seen that the device will also operate efficiently for shorter intermittent periods with the delivery end thereof pointing upward as might be desirable for dusting higher branches or foliage.

To adapt the device for more efficient and convenient dusting of the underside of foliage of plants and bushes, I may provide a curved nozzle 58 which may be mounted on a bracket 59 so as to swing from the inoperative full-line

position shown in Fig. 2 to the broken line position in which one end thereof registers with the opening 26a of the outer cover. When the nozzle is in the latter position, it will be seen that the dust-laden blast of air will be directed in an angular direction to the longitudinal axis of the device for the convenient dusting of the underside of foliage. The curved nozzle 58 can be secured in either of the positions just mentioned by a suitable clamping means, such as the wing nut 60.

In addition to the dusting of plants, my improved device can be used for other purposes, such as that of exterminating rodents and to adapt the device for this use the curved nozzle 58 can be replaced by a straight nozzle 61 to which a hose 62 may be connected, as shown in Fig. 6. During this use of the device, a dust or other chemical poisonous to rodents is placed in the magazine or supply chamber 21 and the blasts of air charged with such poisonous substance are directed through the hose 62 into the den of the rodents. The nozzle 61 may be connected with the dusting device by mounting one side of the nozzle on the bracket 59 as shown in Fig. 6 and securing the opposite side of the nozzle by means of a screw 63 engaging in the threaded opening 64 of the cover 26.

From the foregoing description and the accompanying drawing, it will now be readily seen that I have provided a dusting device in which a more efficient and uniform feeding and distribution of the dust is obtained. It will also be understood that this more efficient action is obtained largely through the use of suction, or suction and an auxiliary air stream or blast combined, for feeding the dust from the supply chamber to the main air blast. Likewise, it will be seen that I have provided a novel valve arrangement by which the feeding of the dust can be controlled or adjusted for obtaining a dust cloud of the desired density. The magazine feature of my device also makes it possible to carry a reserve supply of dust in the device and to easily transfer additional dust from the magazine to the feed chamber without interruption of the dusting operation.

While I have illustrated and described the improved dusting device of my invention in a somewhat detailed manner, it will be understood, of course, that the invention is not to be regarded as limited to the particular form of device and details of construction herein disclosed, but includes all changes and modifications coming within the scope of the appended claims.

Having thus described my invention, I claim:

1. In a device of the character described, a cylinder having an air delivery passage and a piston operable to produce a blast of air in said passage, means adapted to contain a quantity of dust and having an opening into said delivery passage, and a restriction in said delivery passage ahead of said opening and through which the air is forced to produce a suction in said opening for drawing dust into said passage for delivery with the air blast.

2. In a device of the character described, a cylinder having an air delivery tube, a piston operable in the cylinder for delivering a main blast of air through said tube, means providing a chamber adjacent the tube adapted to contain a quantity of dust and a screened passage normally submerged in the dust and connecting such chamber with the tube, and means for causing an auxiliary flow of air through said chamber and

screened passage for feeding dust from the latter into said tube.

3. In a device of the character described, a cylinder having an air delivery tube and a piston operable to produce a blast of air in said tube, means providing a chamber substantially coaxial with said tube adapted to contain a quantity of dust and having an opening connecting the same with said delivery tube, means for causing a flow of air through said opening for feeding dust to said delivery tube, and a rotary valve slideable on the tube and operable to control such feeding of dust.

4. In a device of the character described, a cylinder having an air delivery passage and a piston operable therein for creating a blast of air in said passage, means providing a supply chamber adapted to contain a supply of dust and a feed chamber communicating with the supply chamber and having an opening leading to said delivery passage, and means for causing a flow of air for transferring dust to said feed chamber from said supply chamber and feeding the same through said opening into the delivery passage, said chamber being adapted to retain a quantity of dust adjacent said opening regardless of the position in which the device is held.

5. In a dusting device, a cylinder having an air delivery passage and a piston operable to create a blast of air in said passage, means providing a feed chamber having an opening for feeding dust into said delivery passage, said feed chamber being adapted to maintain a quantity of dust adjacent said opening regardless of the position in which the device is held, a dust supply chamber adjacent such feed chamber, and means for utilizing a portion of said air blast for transferring dust from said supply chamber to said feed chamber.

6. In a dusting device, a cylinder having an air delivery passage and a piston operable to create a blast of air in said passage, means providing a feed chamber having an opening for feeding dust into said delivery passage and a dust supply chamber adjacent such feed chamber, a screen between said supply chamber and said feed chamber, and means for directing a portion of said air blast through said screen for transferring dust from the supply chamber to the feed chamber.

7. In a dusting device, a cylinder having an air delivery passage and a piston operable to create a blast of air in said passage, means providing a chamber adapted to contain a quantity of dust and having an opening leading to said delivery passage, and a restriction in said delivery passage arranged to produce a suction in said opening for feeding dust to the delivery passage.

8. In a dusting device, a cylinder having an air delivery passage and a piston operable to create a blast of air in said passage, means providing a feed chamber having an opening leading to said delivery passage and a dust supply chamber adjacent said feed chamber, means for utilizing a portion of said air blast for transferring dust from said supply chamber to said feed chamber, and a restriction in said delivery passage arranged to produce a suction in said opening for feeding dust from the feed chamber to said delivery passage.

9. In a dusting device having a delivery tube and means for producing an air blast through said tube, a chamber adapted to contain a supply of dust, said tube having a radial opening to said chamber and a restriction ahead of said radial opening for causing a suction in the latter, and a rotary valve substantially coaxial with said tube for controlling the feeding of dust through said radial opening.

10. A dusting device comprising an elongated cylinder having an upper pump section and also having a lower section forming a dust supply chamber, a tube extending axially through said supply chamber, a piston reciprocable in said pump section for creating a blast of air through said tube, a pair of disks mounted in said lower section adjacent the outer end thereof and being spaced apart axially to form an auxiliary dust chamber, said auxiliary dust chamber having screened communication with said supply chamber for receiving dust therefrom and having an opening into said tube, and means providing a restriction in said tube ahead of said opening for inducing a movement of dust through said opening from said auxiliary chamber into said tube.

11. A dusting device comprising an elongated cylinder having an upper pump section and also having a lower section forming a dust supply chamber, a tube extending axially through said supply chamber, a piston reciprocable in said pump section for creating a blast of air through said tube, a pair of disks mounted in said lower section adjacent the outer end thereof and being spaced apart axially to form an auxiliary dust chamber, said auxiliary dust chamber having screened communication with said supply chamber for receiving dust therefrom and having an opening into said tube, means providing a restriction in said tube ahead of said opening for inducing a movement of dust through said opening from said auxiliary chamber into said tube and a rotary valve arranged to control the movement of dust through said opening.

RALPH R. ROOT.
